(57) **CLAIM**

The ornamental design for a grasping cane, as shown and described.

DESCRIPTION

FIG. 1 is a perspective view of a grasping cane showing our new design;

FIG. 2 is a side elevational view thereof;

FIG. 3 is a bottom plan view thereof;

FIG. 4 is a top plan view thereof;

FIG. 5 is a front elevational view thereof; and,

FIG. 6 is a rear elevational view thereof.

The grasping cane is shown broken away in order to indicate that a specific length of the cane forms no part of the claimed design.
